UNITED STATES PATENT OFFICE.

CHARLES H. PETERS, OF BROOKLYN, NEW YORK, ASSIGNOR OF ONE-HALF TO HENRY ANDERMAN, OF NEWARK, NEW JERSEY.

SHOCK-ABSORBER.

1,149,943.

Specification of Letters Patent. Patented Aug. 10, 1915.

Application filed December 31, 1913. Serial No. 809,787.

To all whom it may concern:

Be it known that I, CHARLES H. PETERS, a citizen of the United States, residing at Brooklyn, in the county of Kings and State 5 of New York, have invented new and useful Improvements in Shock-Absorbers, of which the following is a specification.

The general objects of this invention are to refine the construction of shock absorbers 10 for automobiles and like vehicles, in point of promoting the efficiency of the same and in simplifying the manufacture thereof; and further, to effect the shock-absorbing qualities in such a device, by hydraulic and pneumatic means. And to these ends, the invention resides in a tank reservoir, a series of cylinders mounted on the vehicle, and having 15 communications with the tank and further provided with spring-pressed plungers 20 which operate against the water in the tank.

Other objects will appear and be better understood from that embodiment of my invention of which the following is a specification, reference being had to the accompanying 25 drawings, forming part hereof in which:

Figure 1 is a side elevational view of a motor-vehicle showing my invention applied thereto. Fig. 2 is a vertical cross sectional view of a chamber and the plunger operating therein.

The tank 5 may be positioned on the chassis *a* by the supports 6—6 at any convenient location, such as at the center, as 35 shown in the drawings and this tank is provided with an inlet 7, and has openings in the ends such as are designated by 8. Pipes 9—9 are directed into the openings, and connect the tank with the cylinders 10—10, 40 which are mounted on the axles *b*—*b* of the vehicle in any suitable manner, and are attached to the usual elliptical springs *c*, as shown.

The cylinders as shown in Fig. 2, are provided with heads 11, which are detachably secured to the chambers by screw-threads and are provided with centrally located openings 12, and stuffing boxes 13. A piston rod 14 is slidably fitted in this opening and 50 has one end 15 secured to the under portion of the vehicle frame, by any suitable means, such as the bolts 16. The other end of the piston rod is provided with a head 17, which, is of the usual piston-head construction, and 55 is provided with packing rings 18.

A spring 19 is positioned in the chamber under the piston head. A second spring 20 is positioned in the upper part of the chamber, above the piston head, and surrounds the piston rod. The strength of the lower 60 spring is greater than that of the upper.

A regulator 21, is positioned on one of the pipes 9. This regulator consists of a cylinder 22 in which is fitted a plunger 23, operated by a rod 24 which is screw-threaded in 65 the head of the chamber, and is provided with the regulating handle 25. When the tank 5 is originally supplied with water, the plunger 23 of the regulator is adjusted to its uppermost position, and the water, as it 70 flows back and forth through the pipes 9, obviously fills the chamber 22 of the regulator; thus the water contained in the regulator is a surplus quantity and as the total quantity of the water in the tank decreases, 75 the plunger of the regulator is progressed downwardly and the loss in the water is compensated by the reduction in the capacity of the cylinder chamber.

The movement on the part of the plunger 80 23 maintains the air in the chamber 5 at a desired density and consequently desired resiliency may be maintained.

As shown in Fig. 1, a third opening is provided at one end of the tank, and this 85 opening receives a pipe 26, which connects the tank with the water manifold *d* of the motor *a*. This pipe extends into the tank for a greater portion of the length of the tank, and is provided near its mouth with a 90 branch pipe 27, which communicates with the lower part of the radiator of the cooling system. These pipes are provided in the shock-absorbing system for the purpose of preventing the freezing of the water in the 95 pipes and various chambers, for it will be obvious that as the water is circulating in the cooling system of the motor, and is being cooled by the radiator, the water surrounding the motor is relatively warm, and 100 before it reaches the radiator it passes through the tank, thus preventing the temperature of the tank-water from dropping below the freezing point.

The tank 5 and pipes 26 and 27 are supplied with water. However the radiator to which the pipes 26 and 27 are connected is not completely filled with water but a volume of air is permitted to remain therein at the top thereof. As the cylinders 10 move 110

up along the piston head 17 the water is forced back through the pipes 9, tank 5 and the pipes 26 and 27 and consequently the air in the radiator is compressed and acts as means for cushioning the shock to which the vehicle is subjected while moving.

What is claimed as new is:

A shock absorber comprising a tank, a pipe connected with the tank, a cylinder connected with the pipe, a piston movably mounted in the cylinder, a regulator mount-

ed upon the pipe and comprising a cylinder, a plunger movably mounted therein and means for adjusting the position of the plunger in the last mentioned cylinder.

In testimony whereof I affix my signature in presence of two witnesses.

CHARLES H. PETERS.
